JEWELRY CONSTRUCTION

John Sand, Newark, N. J., assignor to Gemex Company, Newark, N. J., a corporation of New Jersey

Application September 14, 1934, Serial No. 744,020

10 Claims. (Cl. 224—4)

This invention relates to jewelry construction and more particularly to an adaptor for use on the end of a bracelet chain or the like.

One of the objects of this invention is to provide a construction of the above character which will be simple, practical and thoroughly durable. Another object is to provide a construction of the above character which may be made from inexpensive materials and whose manufacture is free 5 from complication and detail work. Another object is to provide a construction of the above character which may be easily applied to or removed from a bracelet chain or the like. Another object is to provide a construction of the 10 above character which will be neat and attractive in appearance and yet be of such sturdy construction as to withstand hard usage. Another object is to provide a construction of the above character versatile in use and hence capable of 15 connection with watches having various types of connectors. Another object is to provide an adaptor of the above character which may be removed from or placed upon a bracelet chain a number of times without damage. Other objects 20 will be in part obvious and in part pointed out hereinafter.

The invention accordingly consists in the features of construction, combinations of elements and arrangements of parts, all as will be illustratively described herein, and the scope of the application of which will be indicated in the following claims.

In the accompanying drawing, in which are shown several of the possible embodiments of my 35 invention,

Figure 1 is a plan view of a watch having one type of connector and having attached thereto a bracelet chain with my adaptor connected thereto;

Figure 2 is a plan view of a watch having another type of connector with my bracelet chain connected thereto;

Figure 3 is a vertical sectional view, on an enlarged scale, of my adaptor as applied to a bracelet chain and taken along the line 3—3 of Figure 45;

Figure 4 is a vertical sectional view taken along the line 4—4 of Figure 3;

Figure 5 is a perspective view showing the bottom of my adaptor as applied to the end link of a bracelet chain;

Figure 6 is a perspective view of the end link of a bracelet chain which I prefer to use;

Figure 7 is a perspective view of the bottom of 55 an adaptor forming another embodiment of my

invention as applied to the end link of a bracelet chain;

Figure 8 is an end elevation of the adaptor shown in Figure 7;

Figure 9 is a sectional view of the adaptor 5 shown in Figure 7 as applied to the end link of a bracelet chain, and

Figure 10 is a perspective view of the bottom of the adaptor shown in Figure 7.

Similar reference characters refer to similar 10 parts throughout the several views of the drawing.

As conducive to a clearer understanding of certain features of this invention, it might here be pointed out that watches now on the market are 15 made with various types of connectors and that considerable difficulty has been experienced in designing end links of bracelet chains which are capable of interconnecting with more than one type of connector on a watch. For example, 20 watches are often made with eyes on their opposite ends, the planes of the eyes being substantially perpendicular to the plane of the face of the watch. Many other watches are made with loop connectors, the planes of which are substantially parallel to the plane of the face of the watch. It is very difficult, if not well nigh impossible, to design a link, attractive in appearance, capable of interconnection with either of these connectors now found on so many watches. 25 For this reason a retailer is often forced to carry an unusually large stock of bracelets in order to satisfy the needs of his customers. On each of the various models of bracelets he must have different forms of connecting links so that when a 30 customer selects a particular watch and a particular bracelet the two may be connected. This results in undue expense to the retailer and sometimes inconvenience to the customer if the retailer does not maintain a sufficiently large stock. 35 One of the several objects of this invention is to provide a construction which adequately and efficiently overcomes the above-mentioned difficulties as well as many others.

Referring now to Figure 1, there is shown a 45 watch 10 or the like having a pair of connectors 12 and 13 secured to the opposite sides thereof. Connectors 12 and 13 are substantially parallel to the plane of the face of the watch, and the elongated portions 12a and 13a thereof are 50 spaced from the ends of the watch. A bracelet chain generally indicated at 14 has its end link generally indicated at 15 connected to connector 13 by way of an adaptor generally indicated at 16 to be more fully described hereinafter.

In Figure 2 there is shown a watch 17 having eye connectors 18 and 19 disposed at its opposite sides. Connectors 18 and 19 run in directions substantially perpendicular to the plane 5 of the face of watch 17. Chain 14 is here shown connected to connector 19 by way of end link 15.

As better shown in Figure 6, link 15 comprises leg portions 20 and 21 having formed thereon inwardly extending lugs 22 and 23, these 10 lugs preferably being spaced from the top sides of legs 20 and 21 to form the shoulders 20a and 21a. Also the edges 22a and 23a of lugs 22 and 23 gradually curve inwardly so that the lugs 15 attain a maximum width at the rear ends thereof.

Link 15 may be connected to the remaining links of the chain in any convenient manner as by way of link 24 (Figure 2). It will now become clear that when chain 14 is to be applied to connector 19 of watch 17, it is merely necessary to slip its open ends over the opposite sides of the connector so that lugs 22 and 23 extend inwardly within the eye. If by chance the width of connector 19 is greater than the space between lugs 22 and 23, edges 22a and 23a of the lugs 25 will slide along the opposite sides of the eye 19 spreading legs 20 and 21 and finally snapping into the position shown in Figure 2. If the space between lugs 22 and 23 happens to be greater than the width of eye 19, it is an easy matter to squeeze legs 20 and 21 toward each other to form the interlock with the connector shown in Figure 2. Thus it will be seen that my chain, having end links similar to link 15, is admirably 35 adapted for interconnection with watch 17.

However, when chain 14 is to be secured to connector 13 of watch 10, link 15 thereof is inadequate for this purpose and I accordingly secure thereto the adaptor 16. Adaptor 16 has an 40 elongated hook shaped portion 25 capable of fitting about portion 13a of connector 13. As manufactured, portion 25 is substantially U-shaped but after being slipped over the connector the edge 25a may be bent rearwardly or in a right-hand direction as viewed in Figure 3 to embrace 45 the connector and form a permanent connection therebetween. Secured to the rear side of hook portion 25 is a face plate 26 resting upon lugs 22 and 23 and preferably having its edges tapered and then bent at right angles to the plate to fit 50 snugly against shoulders 21a and 20a as will be clear from a consideration of Figures 1 and 6. The opposite edges of face plate 26 extend downwardly to engage the lugs 22 and 23 (Figure 4) while the central portion 26a is spaced thereabove. Preferably the right angle edge portions 55 of face plate 26 are equal in height to shoulders 20a and 21a so that the top of the face plate lies substantially flush with the top sides of legs 20 and 21, as best seen in Figure 6, thus making 60 for a pleasing and attractive appearance.

Hook portion 25 has formed therein a centrally located slot 27 in which an extension 28 of a fastening part generally indicated at 29 is located. As best shown in Figures 3 and 5, extension 28 is similar in shape to hook portion 25 so that, in effect, it forms a section thereof. Extension 28 is secured to or integral with the bottom 30 of fastening part 29 (Figure 5), this bottom having projections 30a and 30b resting upon 65 the bottom sides of legs 20 and 21. Fastening part 29 thence extends around so that the end portion 31 thereof lies above lugs 22 and 23 and adjacent the bottom side of face plate 26, spaced from and above bottom 30. Portion 31 of fastening part 29 may be secured to face plate 26

in any convenient manner, as, for example, by soldering. Preferably, as best shown in Figure 4, portion 31 is of a width equal to the width of flat portion 26a of the face plate. Accordingly my adaptor includes the face plate 26 resting 5 snugly upon lugs 22 and 23 between shoulders 21a and 20a (Figure 4) together with the fastening part extending along the bottom of link 15 and having an extension which is in reality one section of hook portion 25.

Suppose the link 15 is removed from connector 19 of watch 17 (Figure 2) and it becomes necessary to connect chain 14 to watch 10. Extension 28 of fastening part 29 of an adaptor similar to adaptor 16 is first pressed inwardly toward the 10 interior of hook portion 25 so that the fastening part is bent out to a substantially right angle position with respect to face plate 26. Next extension 28 and bottom 30 of fastening part 29 are slipped between the legs 20 and 21 of the link 15 and thence bent back into their original position against lugs 22 and 23 of the link as described 20 more fully above. The hook portion 25 may now be slipped over connector 13 thence to be bent back upon itself and thus secured in position. The chain 14 is now reliably secured to watch 10, the adaptor 16 being neat in appearance and yet well able to withstand the usual shocks and strains of use. Furthermore, due to the fact that extension 28 extends about connector 13, it is 30 impossible for the adaptor to become accidentally detached from link 15 because extension 28 and bottom 30 of fastening part 29 cannot be bent back to the right angle position as described above for removal until hook portion 25 has 35 been removed from connector 13. It will be observed however that it is a simple matter to bend back hook portion 25 and remove the adaptor from connector 13 of watch 10 after which the adaptor may be removed from the link 15 as described above so that the link 15 may be secured to a watch such as watch 17. Furthermore, adaptor 16 is so sturdy in construction that it 40 may be removed from or secured to link 15 a number of times without damage.

In Figure 7 there is shown another adaptor generally indicated at 32 capable of interconnection with link 15. Adaptor 32 has a hook portion 33 substantially similar in shape and construction to hook portion 25. A face plate 34 is connected to hook portion 33 extending rearwardly therefrom and having longitudinal edges resting upon lugs 22 and 23 and against shoulders 20a and 21a. The rear portion 34a of face plate 34 is preferably bent at right angles to the main portion thereof and has a slot 35 formed therein thus providing a bar portion 34b at the end of face plate 34 substantially adjacent the bottom side of legs 20 and 21 as best seen in Figure 9.

A fastening part generally indicated at 36 is pivotally connected to face plate 34 by a loop portion 37 extending about bar portion 34b. Thus fastening part 36 has a bottom portion 38 extending along the bottoms of lugs 22 and 23 and an extension 39 fitting within a slot 40 located in hook portion 33 (Figures 7 and 8). Extension 39 is provided with ears 39a and 39b substantially at the end thereof interfitting with suitable indentures in slot 40 so that the extension may be 65 snapped into a closed position or that position shown in Figure 7. Extension 39 like extension 28 (Figure 5) has a shape substantially similar to hook portion 33 so that it may lie flush within 70 slot 40.

It will now become clear that adaptor 32 may be applied to or removed from link 15 whenever desired. When the adaptor is to be placed on the link, it is merely necessary to open fastening part 36 swinging it around bar 34b, thence slipping the fastening part through legs 20 and 21 of the link. The fastening part is then snapped into its closed position, as shown in Figure 7, and when the hook portion is closed about connector 13 of watch 10 the fastening part is automatically locked in the closed position and cannot swing about bar 34b to the open position. However it will be apparent that it is very easy to remove adaptor 32 from the link by merely opening up the hook portion 33, removing it from connector 13, and thence opening the fastening part.

It will thus be seen that I have provided a thoroughly practical and efficient construction in which the several objects hereinabove mentioned as well as many others are successfully accomplished.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. As an article of manufacture, an adaptor capable of interconnection with a loop on a watch running parallel with the plane of the face of said watch and the end link of a bracelet chain, said link being U-shaped and having lugs formed on the legs thereof extending toward each other comprising an elongated hook portion adapted to fit about said loop, a face portion extending rearwardly therefrom over the tops of said lugs, said hook portion having a centrally located slot, and a part corresponding in shape to said hook portion fitting within said slot thence extending rearwardly over the bottoms of said lugs and bent back upon itself and secured to said face portion.

2. As an article of manufacture, an adaptor capable of interconnection with a loop on a watch running parallel with the plane of the face of said watch and the end link of a bracelet chain, said link being U-shaped and having lugs formed on the legs thereof extending toward each other comprising an elongated hook portion adapted to fit about said loop, a face portion extending rearwardly therefrom over the tops of said lugs, said hook portion having a centrally located slot, and a part corresponding in shape to said hook portion fitting within said slot thence extending rearwardly over the bottoms of said lugs and bent back upon itself and secured to said face portion, said part capable of being bent outwardly from said slot and away from said lugs so that said adaptor may be removed from said leg.

3. As an article of manufacture, an adaptor capable of interconnection with a loop on a watch running parallel with the plane of the face of said watch and the end link of a bracelet chain, said link being U-shaped and having lugs formed on the legs thereof extending toward each other comprising an elongated hook portion adapted to fit about said loop, a face portion extending rearwardly therefrom over the tops of said lugs, said hook portion having a centrally located slot, and a part corresponding in shape to said hook portion fitting within said slot thence extending rearwardly over the bottoms of said lugs and bent back upon itself and secured to said face

portion, said part having lateral projections extending over and resting upon the legs of said link.

4. As an article of manufacture, an adaptor capable of interconnection with the end link of a bracelet chain and a loop on the end of a watch running substantially parallel to the plane of the face of said watch comprising, an elongated hook portion adapted to interfit with said loop, a face portion extending rearwardly therefrom over portions of said link, and a bottom plate hingedly connected to the end of said face portion and adapted to fit down upon the bottom side of said link.

5. As an article of manufacture, an adaptor capable of interconnection with the end link of a bracelet chain and a loop on the end of a watch running substantially parallel to the plane of the face of said watch comprising, an elongated hook shaped portion adapted to fit about said loop, a face portion extending rearwardly therefrom over the top surface of said link, and a bottom portion hingedly connected to the end of said face portion and resting upon the bottom side of said link and interfitting with a slot substantially centrally located in said hook portion.

6. As an article of manufacture, an adaptor capable of interconnection with a loop on a watch running parallel with the plane of the face of said watch and the end link of a bracelet chain, said link being U-shaped and having lugs formed on the legs thereof extending toward each other, comprising a hook portion adapted to interfit with said loop, a face plate extending rearwardly therefrom over the top sides of said lugs, and a bottom plate hingedly connected to the end of said face plate and adapted to rest upon the bottom sides of said lugs.

7. As an article of manufacture, an adaptor capable of interconnection with a loop on a watch running parallel with the plane of the face of said watch and the end link of a bracelet chain, said link being U-shaped and having lugs formed on the legs thereof extending toward each other, comprising a hook portion adapted to interfit with said loop, a face plate extending rearwardly therefrom over the top sides of said lugs, and a bottom plate hingedly connected to the end of said face plate to rest upon the bottom sides of said lugs and interfitting with a centrally located slot in said hook portion.

8. In jewelry construction, in combination, a watch, a pair of bar members secured to the opposite ends of said watch and spaced from the ends of said watch, a bracelet chain, said bar members being capable of attachment to the opposite ends of said chain, the end links of said chain being U-shaped, and having inwardly extending projections formed substantially at the opposite ends of the legs thereof, and adaptors each comprising an elongated hook shaped portion adapted to fit about one of said bar members, a top face portion extending rearwardly from and connected to said hook shaped portion and resting upon said projections, and a bottom member forming a part of said hook-shaped portion extending rearwardly over the bottoms of said projections and bent upon itself to be secured to the bottom side of said face portion.

9. In jewelry construction, in combination, a bracelet chain having U-shaped end links with lugs extending toward each other from the opposite end portions of the legs of said links, said links adapted to interlock with eye members on a watch, the axes of which are substantially parallel to

the plane of the face of the watch, and adaptors each capable of forming connections with loop members on the ends of another watch, said loop members being substantially parallel to the planes 5 of the ends of said last-mentioned watch, said adaptors each comprising a hook-shaped portion adapted to fit about one of said loops, a face portion extending rearwardly over the top surface of said lugs on said links and connected to said 10 hook-shaped portion, and a part forming a portion of said hook thence extending rearwardly

therefrom over the bottom surface of said lugs bent back upon itself and connected to said face portions.

10. As an article of manufacture and adapted for connection to the bail of a watch, an adaptor comprising a bendable hook-shaped portion having a cut-out portion therein, a top plate extending from said hook-shaped portion, and a bottom plate hingedly connected to said top plate and swingable into said cut-out portion. 10

JOHN SAND.
